UNITED STATES PATENT OFFICE.

RUDOLF ROSNER, OF CHICAGO, ILLINOIS, ASSIGNOR TO CARTER-LONG MAGNETO COMPANY, OF WAUKEGAN, ILLINOIS, A CORPORATION OF ILLINOIS.

INDUCTION-COIL.

1,332,757.

Specification of Letters Patent. Patented Mar. 2, 1920.

Application filed February 23, 1918. Serial No. 218,876.

To all whom it may concern:

Be it known that I, RUDOLF ROSNER, a citizen of the United States, residing at Chicago, in the county of Cook and State of Illinois, have invented certain new and useful Improvements in Induction-Coils, of which the following is a specification, reference being had to the accompanying drawings, forming a part thereof.

10 The purpose of this invention is to provide an improved construction of secondary or induction coils. It consists in the elements and features of construction shown and described, as indicated in the claims.

15 In the drawings:

Figure 1 is an axial section of an inductorium or induction coil embodying this invention.

Fig. 2 is a section at the line, 2--2, on Fig. 1.

Fig. 3 is a perspective view of one of the core strips characteristic of the invention, the same being shown somewhat exaggerated in thickness.

25 In the structure shown in the drawings, A and B, are two concentric tubes of suitable dielectric material whose annular interspace contains the core of the induction coil, which consists of a multiplicity of thin flat soft

30 iron strips, C, each completely coated as to all sides and ends with insulations such, for example, as a film of linseed oil, so as to afford effective insulation with the least sacrifice of space, and permit the largest possible mass of soft iron core within the given

35 space. The entire group of soft iron strips, C, is embedded in suitable insulations such as fiber, indicated at D, which occupies the entire space between the tubes A and B,

40 around a group of core strips, covering the same at the ends as well as around the outside and inside of the group. E represents the primary circuit winding, F the secondary circuit winding. It will be understood

45 that the primary winding is in circuit with a source of current with a suitable interrupter in the circuit, and that the secondary

circuit is connected according to the service to be performed, none of these connections of either circuit being shown.

50

Two principal advantages pertain to the employment of the flat metal core strips instead of the more usual bundle of round wires: First, the flat metal strips being assembled all in parallel planes, as indicated 55 in the section, Fig. 2, there is no waste space, the minimum thickness of insulating material on the soft iron strip constituting the entire separation between said metal strips, whereas, in the case of round wire, the wires 60 being separated from each other at their lines of nearest contact by the minimum thickness of material necessary for insulation, having much larger interspaces throughout the entire remainder of their 65 circumference; secondly; substantially perfect parallelism of all the flat strips can be obtained, whereas in the case of a bundle of round wires it is practically impossible to effect their assemblage or aggregation in the 70 form of an annular core without many instances of obliquely or angularly placed wires crossing each other with the effect of partial opposition and neutralization of their respective lines of force, and consequent 75 diminution of the resulting secondary current.

I claim:

1. An induction coil of which the core is annular in cross-section and composed of 80 thin flat soft iron strips individually insulated from each other, in combination with concentric di-electric-containing tubes, in whose annular interspace the core is situated.

2. In an induction coil such as defined in 85 claim 1, the strips being embedded and completely inclosed in insulation occupying the remnants of the annular interspace between the di-electric tubes around the core strips 90 therein.

In testimony whereof, I have hereunto set my hand at Chicago, Illinois, this 18th day of February, 1918.

RUDOLF ROSNER.
